UNITED STATES PATENT OFFICE.

RUFES M. LOVELACE, OF CROWDER, OKLAHOMA.

ANTICREEPER RAIL PLATE.

Application filed February 23, 1924. Serial No. 694,749.

To all whom it may concern:

Be it known that I, RUFES M. LOVELACE, a citizen of the United States, residing at Crowder, in the county of Pittsburg and 5 State of Oklahoma, have invented certain new and useful Improvements in Anti-creepers Rail Plates, of which the following is a specification.

This invention relates to anti-creepers rail 10 plates and it consists in the novel features hereinafter described and claimed.

An object of the invention is to provide a plate of simple form adapted to be applied to the tie and rail of a railway track 15 structure and which will prevent the rail from slipping or running longitudinally over the tie toward low places in the road bed.

The fact is well known that unless means 20 are provided for restraining track rails against creeping, they move longitudinally under the influence of the traffic passing over them or they slide down inclined stretches 25 of the road, and the sections tend to crowd or accumulate at low places and in extremely 30 warm weather, the sections of the rails expand longitudinally and some of the sections are liable to kink or bow whereby they are thrown out of true alignment and such distortion frequently results in accident due to derailment of the rolling stock.

Therefore it is the object of the present 35 invention to provide simple means, such as stated, to prevent the rail sections from creeping and to positively confine them in their proper and prescribed relation with respect to each other, with respect to the ties, and with respect to the road bed.

In the accompanying drawing: 40 Figure 1 is a fragmentary plan view of a track rail showing the anti-creepers plate applied thereto.

Figure 2 is an edge elevation of the anti-creepers plate.

Figure 3 is an enlarged fragmentary end elevation of the anti-creepers plate viewing the same at the opposite end from that end which is shown in Figure 2.

The anti-creepers rail plate comprises a 50 body portion 1 which is preferably rectangular in plan and which is provided at one side portion with a curved lip 2 which extends the full transverse breadth of said body. The body portion 1 is provided in

the vicinity of one corner thereof and at a 55 point between the curved edge of the lip 2 and the adjacent edge of the body with a spike opening 3. The body portion 1 is provided in the vicinity of its diagonally opposite corner with a spike opening 4 and 60 an upstanding lug 5 is provided upon the upper face of the body 1 between the outer edge of the spike opening 4 and the adjacent edge of the said body 1. The body portion 1 is provided at the same 65 side portion as that at which the opening 4 and the lug 5 are located with a prong portion 6. The end portion of the prong 6 is sheared off diagonally whereby a vertical 70 edge 7 is provided at the end of the said prong, the said edge 7 being in alinement with the adjacent side edge of the body 1. The prong 6 is also provided at its under 75 side with relatively sharp edges 8 and 9 which converge toward the edge 7 and which are adapted to bite into the upper surface of the base flange of the rail when the anti-creepers plate is applied. The rail is indicated at 10. The inner edge surface of the 80 lip 2 is cut away at 11 at one end of the said lip in order that the body 1 of the plate may assume the position with relation to the rail as indicated in dotted lines in Figure 1 of the drawing when the plate is being applied to the rail. To apply the plate to 85 a rail, the same is first turned to an angle with respect to the rail, as indicated by the dotted line and slightly tilted with respect to the plane of the base flange of said rail, so that the lip 2 may be inserted over the 90 base flange of the rail at one side, following which the prong 6 is moved upwardly 95 beyond the base flange, at the other side of the rail, the plate still retaining an inclined relation with respect to the base flange of the rail, due to the contact of the lug 5 with the bottom thereof. The inclination of the lip 2 is sufficient to permit a substantial amount of play between the base flange of the rail and the lip, to allow the plate to be 100 positioned in inclined relation under the bottom of the rail during its turning movement, in order to move the lug 5, which is 105 relatively small in height, past the edge of the base flange of the rail into the full line position of Figure 1. Following this partial application of the plate, the same is rotated to the transverse position, shown in

full lines in Figure 1, from the dotted line position, in order that the lug 5 may be moved outwardly beyond the side edge of the base flange of the rail, in order to move 5 the plate upwardly so that the base of the plate contacts with the base of the rail, following which the same is ready for spiking to the tie. When the plate is positioned, as illustrated in full lines, in Figure 1, spikes 10 may be driven through the openings 3 and 4, so that the plate is fastened to a tie and held in locked relation, in connection with the rail, the lip 2 and prong 6, in this relation, firmly engaging the face of the base flange 15 of the rail, and serving in cooperation with the spikes driven through the openings 3 and 4, to retain the rail relative to the tie, and prevent creeping thereon. Thus when the spikes are driven and the plate is applied 20 to the rail as indicated, the rail is positively held against longitudinal movement with relation to the tie thus preventing creeping and the objectionable features incident thereto.

Having described the invention, what is 25 claimed is:

An anti-creeping rail plate comprising a body having at one side portion a lip extending from edge to edge of the body and provided at one end with an inner cut away 30 wall portion, spike openings passing through the body and located in the vicinity of diagonally opposite corners thereof, a lug formed upon the body at the side of one of the spike openings, a prong formed upon 35 the body and having a pointed end disposed toward the opposite spike opening, the inner end of the prong being sheared diagonally whereby a vertically disposed sharp edge is provided at the extremity of the prong, said 40 edge being located in the same plane as the adjacent edge of the body and the converging edges of the prong being sharpened at the lower face of the prong and adapted to cut into the base flange of a rail when a 45 plate is applied.

In testimony whereof I affix my signature.
RUFES M. LOVELACE.
